CLAIM

The ornamental design for a purse with garment front and sleeve ties, as shown and described.

DESCRIPTION

FIG. 1 is a top perspective view of a purse with garment front and sleeve ties showing my new design, it being understood that the phantom lines are to illustrate its use only and form no part of the claimed design;

FIG. 2 is a top perspective view of the opposite side of FIG. 1.

FIG. 3 is a front elevation view thereof;

FIG. 4 is a top plan view thereof;

FIG. 5 is a rear elevation view thereof;

FIG. 6 is an enlarged, fragmentary, top plan view thereof;

FIG. 7 is an enlarged, fragmentary, bottom plan view thereof; and,

FIG. 8 is an enlarged side elevation view thereof with the other side being a mirror image.
